Primary Examiner — Bobby Muromoto, Jr.(74) *Attorney, Agent, or Firm* — Wood, Phillips, Katz, Clark & Mortimer(57) **ABSTRACT**

A protective hood for use by a firefighter or other emergency worker. The hood includes a crown portion to cover the top of a wearer's head, the crown portion being made from a material having a primary stretch direction oriented to extend in a transverse, ear-to-ear, direction across the top of a wearer's head; and a lower portion that extends downward from the crown portion, the lower portion being made from a material having a primary stretch direction oriented to extend in a circumferential direction around a wearer's head.

FIELD OF THE INVENTION

This invention pertains to protective hoods, such as a protective hood worn by a firefighter or other emergency worker.

BACKGROUND OF THE INVENTION

Protective hoods, such as those used by firefighters are exemplified in U.S. Pat. Nos. 4,972,520; 5,090,054; 5,873,132; and 6,662,375, the disclosures of which are incorporated herein by reference, and are available commercially from Morning Pride Manufacturing, L.L.C. of Dayton, Ohio. Additionally, protective hoods are also used by others such as race car drivers, rescue workers and other emergency personnel.

It is common for a protective hood such as worn by firefighters and other emergency workers to be made from a knit material that stretches in the circumferential direction C around the head of the wearer for fit and ease of donning the hood, as shown in FIG. 1. However, because the knit material does not have the same ability to stretch in the longitudinal direction L, extra fabric will often remain at the crown of the head after it is donned, as seen in FIGS. 1 and 2. This extra material can become an irritant to a wearer, and/or interfere with other protective gear, such as a protective helmet.

SUMMARY OF THE INVENTION

A protective hood is provided for use by a firefighter or other emergency worker. The hood includes a crown portion to cover the top of a wearer's head, the crown portion being made from a material having a primary stretch direction oriented to extend in a transverse (ear-to-ear) direction across the top of a wearer's head; and a lower portion that extends downward from the crown portion, the lower portion being made from a material having a primary stretch direction oriented to extend in a circumferential direction around a wearer's head.

Other objects, features, and advantages of the invention will become apparent from a review of the entire specification, including the appended claims and drawings.

BRIEF DESCRIPTION OF THE DRAWINGS

FIG. 1 is a front perspective view of a prior art protective hood in a donned position on a wearer;

FIG. 2 is a perspective view from above of the prior art protective hood and wearer of FIG. 1;

2

FIG. 3 is a front perspective view of a protective hood embodying the invention in a donned position on a wearer; and

FIG. 4 is a perspective view from above of the protective hood and wearer of FIG. 3.

**DETAILED DESCRIPTION OF THE PREFERRED
EMBODIMENT**

- 10 With reference to FIGS. 3 and 4, a protective hood 10 is provided and includes a crown portion 12 and a lower portion 14 extending downward from the crown portion 12 to preferably cover the back, sides, and front of a wearer's head with a window opening 16 for at least the eyes of the wearer. A circumferential seam 18 connects a perimeter of the crown portion 12 with the lower portion 14. The window opening 16 is preferably defined by a peripheral bead or seam 20 that can elastically expand to conform to shape of the wearer's face and a desired opening size.
- 15 The crown portion 12 and lower portion 14 are made from a knit material 22 that has a primary stretch direction S in which the material stretches relatively easily in comparison to an orthogonal direction O. As best illustrated in FIG. 4, the lower portion 14 is oriented so that the material 22 stretches circumferentially around the head, with the stretch direction S aliened circumferentially. The material 22 of the crown portion is rotated with respect to the orientation of the material 22 of the lower section so that the material 22 stretches transversely across the crown of the head. It should be appreciated that by providing the crown portion 12 that is stretchable in the transverse direction together with the lower portion 14 that is stretchable in a circumferential direction, the hood 10 can provide a good fit both the circumference of the head and the top of the head.
- 20 The knit material 22 can be made from a variety of materials known to those skilled in the art, including for example NOMEX® knit material. Preferably, the material 22 should be fire resistant and thermally insulative to protect the wearer.
- 25 The invention claimed is:
- 30 1. A protective hood, the hood comprising:
a crown portion to cover the top of a wearer's head, the crown portion being made from a material having a primary stretch direction oriented to extend in a transverse direction across the top of a wearer's head, the material's ability to stretch in the primary stretch direction being superior to the material's ability to stretch in a direction orthogonal to the primary stretch direction; and
- 35 a lower portion that extends downward from the crown portion, the lower portion being made from a material having a primary stretch direction oriented to extend in a circumferential direction around a wearer's head, the material's ability to stretch in the primary stretch direction being superior to the material's ability to stretch in a direction orthogonal to the primary stretch direction.
- 40 2. The hood of claim 1 wherein an opening is provided in the lower portion for at least the eyes of a wearer.
- 45 3. The hood of claim 2 wherein the opening is defined by a peripheral seam that can elastically expand to conform to the shape of a wearer's face and a desired opening size.
- 50 4. The protective hood of claim 1 wherein the material of the crown portion is a knit material and the material of the lower portion is a knit material.
- 55 5. The protective hood of claim 1 wherein a circumferential seam connects a perimeter of the crown portion to the lower portion.

6. A protective hood, the hood comprising:

a crown portion to cover the top of a wearer's head, the crown portion being made from a knit material having a primary stretch direction oriented to extend in an transverse direction across the top of a wearer's head, the material's ability to stretch in the primary stretch direction being superior to the material's ability to stretch in a direction orthogonal to the primary stretch direction;

a lower portion that extends downward from the crown portion, the lower portion being made from a knit material having a primary stretch direction oriented to extend in a circumferential direction around a wearer's head, the material's ability to stretch in the primary stretch direction being superior to the material's ability to stretch in a direction orthogonal to the primary stretch direction; and

an opening provided in the lower portion for at least the eyes of a wearer.

7. The protective hood of claim 6 wherein the opening is defined by a peripheral seam that can elastically expand to conform to the shape of a wearer's face and a desired opening size.

8. The protective hood of claim 6 wherein a circumferential seam connects a perimeter of the crown portion to the lower portion.

5

10

15

20

25

9. A protective hood, the hood comprising:

a crown portion to cover the top of a wearer's head, the crown portion being made from a material having a primary stretch direction oriented to extend in an transverse direction across the top of a wearer's head, the material's ability to stretch in the primary stretch direction being superior to the material's ability to stretch in a direction orthogonal to the primary stretch direction; a lower portion that extends downward from the crown portion, the lower portion being made from a material having a primary stretch direction oriented to extend in a circumferential direction around a wearer's head, the material's ability to stretch in the primary stretch direction being superior to the material's ability to stretch in a direction orthogonal to the primary stretch direction, a circumferential seam connecting a perimeter of the crown portion to the lower portion; and

an opening provided in the lower portion for at least the eyes of a wearer.

10. The protective hood of claim 9 wherein the opening is defined by a peripheral seam that can elastically expand to conform to the shape of a wearer's face and a desired opening size.

11. The protective hood of claim 9 wherein the material of the crown portion is a knit material and the material of the lower portion is a knit material.
